UNITED STATES PATENT OFFICE.

CLARENCE F. POCLE, OF EVANSTON, ILLINOIS, ASSIGNOR TO GOODMAN MANUFACTURING COMPANY, OF CHICAGO, ILLINOIS, A CORPORATION OF ILLINOIS.

DRAFT-OPERATED SCRAPER.

Application filed December 13, 1923, Serial No. 689,326. Renewed March 28, 1927.

This invention relates to improvements in draft operated scrapers used for gathering and transporting loose material and has for its principal object to produce an improved form of scraper capable of being initially deflected from its normal path of movement to gather loose material distributed over relatively wide areas. A further object is to provide an improved method of gathering 10 coal or the like from a mine room.

More specifically the present invention relates to improvements in scraper loading systems of the type disclosed in Patent No. 1,408,080, issued February 28, 1922, to 15 Charles E. Davis, which is especially designed for use in loading out coal or similar loose material from adjacent working faces of mine rooms. Such scrapers are adapted for reciprocal movement by means of a head rope and a tail rope, the tail rope having movable connection at the rear end of 20 the scraper. Means are further provided for engaging and retarding the outer side of the scraper, i. e., the side away from the 25 working face, so that when the scraper is drawn rearwardly into the far corner of the room its initial forward movement will be directed toward the working face to gather the loose material, especially in the corner of 30 the room.

The present invention consists primarily in combining with an apparatus as above described a pivotally opening scraper such as was disclosed in the application of Charles 35 E. Davis, bearing Serial Number 627,548, filed March 26, 1923, whereby the operation of the scraper is facilitated and made semi-automatic, as will hereinafter more fully appear. The present invention also provides 40 improvements in the details of construction of a pivotally opening scraper.

Details of the invention may be best understood by reference to the accompanying drawings, in which:

45 Figure 1 is a rear view in perspective of a scraper constructed in accordance with my invention;

Figure 2 is a plan view of the scraper showing it in closed position in full lines and 50 partially open in dotted lines;

Figures 3, 4, 5 and 6 are views illustrating a typical installation of the scraper in a mine and showing the scraper in four different positions during its loading operation.

Referring now to details, the scraper comprises a body made up of two side walls, 10, 11, preferably diverging from the rear to the front end thereof, although other forms and shapes of scraper body may be provided, if desired. The scraper is preferably bottomless, the walls 10 and 11 being provided with inwardly extending flanges 12, 12 along their lower margins to form cutting edges for engaging the material to be gathered. The walls 10 and 11 are pivotally connected by a hinge, which may be of any suitable form, for instance, it may comprise a pair of eyes 13, 13 on one wall 10, and an intermediate eye 14 on the other wall 11, 60 with a hinge pin 15 of any approved pattern extending therethrough. As shown herein the side walls 10, 11 are hinged centrally of the rear end although under some conditions it may be desirable to vary the position of the hinged connection toward one side of the scraper. 65

Means are provided for limiting the movement of the scraper sides toward each other. In the form shown this means comprises a 80 pair of telescoping members 16 and 17 pivotally connected respectively near the forward ends of the scraper walls. As shown herein the member 16 comprises a bar and is movable longitudinally in a hollow pipe forming the member 17. The arrangement is such that the free end of the pipe 17 engages a stop 18 on the bar to limit the inward movement of the walls 10 and 11. 85

Draft means for the scraper comprises a 90 head rope 20 connected to the forward end of the scraper by suitable means such as the terminals 21, 21, secured respectively to the forward ends of the side walls 10 and 11, and a tail rope 22 movably connected to the rear end of the scraper. As shown herein the tail rope connection comprises a suitable link 23 movable along a rod or bar 24 having connection at its rear end to one of the side wall members, such as the wall 10, and extending forwardly around this wall to a point intermediate the ends of the scraper. The link 23 may freely move along the bar 24 during the operation of the scraper, as will hereinafter more fully appear. It is 100 also preferable to provide a rearwardly extending notch 25 on the bar 24 at a point substantially in a longitudinal center line of the scraper, that is to say, in alignment with the pivotal point of the two side walls 10 and 110

11. The scraper is also provided with a hook or stop 26 attached to the side wall 11, opposite the sliding connection with the tail rope just described.

5 The use and operation of the scraper above described will be understood by reference to Figures 3, 4, 5, and 6, illustrating its use in a mine room. In this instance the scraper is being used for gathering loose material 10 adjacent the working face, indicated at 30. A side wall or rib 31 meets the working face 30 at an angle, forming a corner as shown in these figures. In Figure 3 a pile of loose material has been deposited on the floor adjacent the working face, the toe or forward edge of this pile being indicated at 32. The portion of the loose material adjacent the side wall 31 is preferably cleared away for a purpose that will presently appear. The 20 scraper is installed for reciprocable movement in the usual manner along the working face as well known to those familiar with mining methods. The tail rope 22 is trained over a sheave or guide 34 fixed by a jack or 25 similar means against the side wall or rib 31 and adjacent the working face 30 substantially as shown in the diagram. A suitable stop may comprise a jack 35 of the usual kind arranged adjacent the sheave 34 but 30 spaced therefrom in the path of rearward movement of the scraper and on the outer side of the tail rope 22.

In the loading operation the scraper is 35 pulled rearwardly by the tail rope into the position substantially shown in Figure 4, in which position it will be noted that the stop 26 on the scraper is brought into engagement with the fixed jack 35. This will retard the side 11 of the scraper so as to cause an unbalanced tension of the scraper, tending to 40 swing it pivotally toward the working face 30. As this swinging movement begins the link 23 is free to move along the bar 24 into position substantially as shown in Figure 4. 45 This movement of the link tends to swing the scraper side 10 pivotally on its hinge into open position as shown in Figure 5. In this position it will be observed that the hinged portions 10 and 11 are spread apart 50 so that the head rope terminals 21, 21 are substantially in a straight line to limit further movement of said walls. The scraper is thus automatically brought into 55 position to initially engage the pile of loose material while directed toward the working face. The initial forward movement is commenced by placing tension on the head rope 21. It will be observed that the initial draft on the head rope will be exerted directly on 60 the inner hinged wall 10 so that the movement of the scraper will be initially deflected from its normal path of forward movement due to the greater resistance of the material engaged by the inner wall 10. Thus the 65 scraper not only is automatically directed

toward the working face before its initial forward movement, but also has a tendency to hug the working face when it gets underway. When the load is gathered it is pulled forwardly to the point of discharge in the 70 usual manner and then returned for another load, whereupon the operation above described is repeated.

Although I have shown and described one form in which my invention may be embodied, it will be understood that the construction and arrangement of the parts may be altered without departing from the spirit and scope of my invention. I do not therefore, wish to be understood as limiting myself to the specific construction illustrated herein excepting as specifically limited in the appended claims.

I claim as my invention:

1. A scraper provided with forwardly extending walls movable laterally with respect to each other, a rope having movable connection with said scraper at the rear end thereof, and means for retarding the movement of the scraper at a point on one side 80 thereof during its normal movement in the rearward direction.

2. A scraper provided with forwardly extending walls movable laterally with respect to each other, means for limiting the inward movement of said walls, a head rope, and a tail rope having slidable connection along the rear and side of said scraper.

3. A scraper provided with forwardly extending walls movable laterally with respect to each other, means for limiting the inward movement of said walls, a head rope, a tail rope having slidable connection along the rear and one side of said scraper, and a projection on the other side of the scraper 100 adapted to engage a fixed support.

4. In a scraping apparatus, a scraper provided with forwardly extending walls movable laterally respective to each other, means limiting the inward movement of said walls, a drag line having two terminal members each connected with one of said walls, the total length of said terminal members being greater than the distance between their respective points of connection with the side walls when the latter are in closed position, and a tail rope having slidable connection along the rear end and one side of said scraper.

5. In a scraping apparatus, a scraper provided with forwardly extending walls movable laterally respective to each other, means limiting the inward movement of said walls, a drag line having two terminal members each connected with one of said walls, the total length of said terminal members being greater than the distance between their respective points of connection with the side walls when the latter are in closed position, a tail rope having slidable connection along 120

the rear end and one side of said scraper, and a projection on the other side of the scraper adapted to engage a fixed support.

6. The method of handling a rope operated scraping device which consists in positioning a fixed member at a predetermined position in the rearward line of movement of the scraper, pulling the scraper rearwardly to engage said member at a point on one side of the scraper and continuing the rearward pull on said scraper with said fixed member as an axis to shift a movable side

wall portion of said scraper laterally into position to engage a portion of the material to be gathered, and thereafter causing tension to be placed on the drag line whereby the resistance of the material engaged by said movable wall portion will cause the entire scraper to be initially deflected at an angle to the drag line. 15

Signed at Chicago, in the county of Cook and State of Illinois, this 10th day of December, A. D. 1923.

CLARENCE F. POOLE.
